Atty.

UNITED STATES PATENT OFFICE.

JAMES J. DEVINE, OF PHILADELPHIA, PENNSYLVANIA.

BOLT.

SPECIFICATION forming part of Letters Patent No. 315,748, dated April 14, 1885.

Application filed October 3, 1884. (No model.)

To all whom it may concern:

Be it known that I, JAMES J. DEVINE, a citizen of the United States, residing at Philadelphia, in the county of Philadelphia and State of Pennsylvania, have invented new and useful Improvements in Bolts, of which the following is a specification.

My invention has relation to improvements in sliding bolts, and is specially intended to provide means for fastening a sliding bolt securely in position when it is shot home in the locking bearing or staple.

My improvements are fully described hereinafter, and the same clearly shown in the accompanying drawing, forming a part of this specification. I have also specifically pointed out the novelty in the claim hereto made, as required by statute.

In the drawing, the letter A represents the base-plate, provided with the usual bearings or sleeves, a, to receive the bolt, and having perforations by which it may be secured in position.

The letter B represents the sliding bolt, which is of the flat variety, fitted to the bearers or sleeves, and has a finger lug or projection by which it is moved back and forth in the bearers.

The letter C represents the keeper or catch-piece, usually fixed to the frame of the door, to receive the free end of the sliding bolt.

To the sliding bolt at a point, a', so that its distance of slide shall not be interfered with, is pivotally secured a locking-lever, D. This locking-lever is pivoted to the sliding bolt at a point which, when the bolt is shot forward, shall set the base of the lever against the forward bearer, and the length of the locking-lever is such that when the bolt is shot forward the free end of the lever shall set against the edge of the rear bearer, substantially as shown in the drawing. The locking-lever is provided with a finger-hold, b, by which it may be lifted or placed in position, and the free end is formed with an inwardly-extending lip or flange, c, to prevent the lever from dropping below horizontality when in locking position.

The position of the locking-lever when not in locking engagement is shown in the drawing by dotted lines.

The invention is particularly adapted to be applied to a flat sliding bolt, and when so

used, it is readily seen, the device operates to effectually bar the bolt against backward movement. 55

The operation is at once apparent on examination of the drawing. The bolt is slid forward, and the limit of motion being reached the locking-lever falls with its free end against the edge of the bearer on the plate, and the bolt is fastened in such position until released by lifting the lever and drawing the bolt back.

I am aware that a door-latch has been made wherein a catch is extended through a slot in the rear edge of the lock-casing and formed with notches to set over the edge of the plate of the casing to hold the bolt in a locked or unlocked position, and that a spring-lock has been made with the rear end of the bolt projecting from the lock-casing, and having pivotally attached to it a lever adapted to be turned with its side or end against the outside of the end of the lock-casing. Further, I am aware that a door-bolt has been made 75 wherein the bolt is chambered out on one side and formed with a central longitudinal slot, and a lever with a pivotal bearing in said slot arranged to turn into horizontal position against the end walls of the chamber in 80 the bolt to hold it locked or unlocked. A nut and bolt lock has been made having a cam pivoted to a slotted lock-plate, which cam, when swung against a nut screwed on the bolt projected through the plate, holds the lock- 85 plate from moving horizontally.

My improvements are particularly applicable to a sliding bolt held in bearers, and consist in the specific construction stated in the claim. 90

What I claim is—

In combination with the base-plate and its bearers, and the flat sliding bolt fitted to move in the bearers, a locking-lever pivotally secured to the bolt, so that when the bolt is shot forward the locking-lever shall fall parallel with the bolt and between two bearers of the base-plate, substantially as and for the purpose set forth. 95

In testimony whereof I have hereunto subscribed my name in the presence of two attesting witnesses. 100

JAMES J. DEVINE.

Attest:

EDMUND B. SEYMOUR,
JOSEPH J. FAY.
